(57) **CLAIM**

The ornamental design for a microdebrider, as shown and described.

DESCRIPTION

FIG. 1 is a perspective view of the device;

FIG. 2 is a front elevational view of the device;

FIG. 3 is a back elevational view of the device;

FIG. 4 is a top view of the device;

FIG. 5 is a bottom view of the device; and,

FIG. 6 is a side elevational view of the device, the other side being a mirror image.

In the drawings, the broken lines depict environmental subject matter and form no part of the claimed design.
